UNITED STATES PATENT OFFICE

2,016,747

TIE CLASP

Albert A. Kaplan and Emanuel Porcelain,
Bronx, N. Y.

Application May 23, 1934, Serial No. 727,050

4 Claims. (Cl. 24—85)

This invention relates to tie clasps.

An object of this invention is to provide a device of the character described, adapted to be removably attached to the inner folds of a tie and being further provided with means for clasping the same to the front of the shirt whereby the tie may be held in proper position.

Another object of this invention is to provide a neat, compact and durable device of the character described, which shall be comparatively inexpensive to manufacture, comprise few and simple parts, be easy to assemble and manipulate, and which shall nevertheless be practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is a front perspective view of a shirt and tie provided with a device embodying the invention for holding the tie in proper position;

Fig. 2 is a cross-sectional view taken on line 2—2 of Fig. 1;

Fig. 3 is a cross-sectional view taken on line 3—3 of Fig. 1;

Fig. 4 is a front elevational view of my improved device with the pin swung open;

Fig. 5 is a rear elevational view of said device;

Fig. 6 is a side view of a device embodying the invention and illustrating a modified construction; and

Fig. 7 is a cross-sectional view taken on line 7—7 of Fig. 6.

Referring now in detail to the drawing, 10 designates a shirt having overlapping edges 11 and 12 buttoned to each other in the usual manner.

In the drawing, 13 represents an ordinary four-in-hand tie. Our improved device 15, for removably attaching the tie to the edge of the shirt, comprises a U-shaped plate 16 having folded over substantially parallel portions 17 and 18 interconnected by the curved portion 19 at one end.

The plate 16 may be made of metal and the portion 17 thereof is provided with a pair of parallel ears 20 preferably cut from the metal thereof and bent into perpendicular relation with respect to the plane of said portion. A transverse rivet 21, fixed to the ears 20, which are

perforated for the purpose, serves as a pivotal mounting for an elongated pin 24 having a loop or eye 25 at one end receiving said rivet. The pin 24 is pointed at the outer end 25a.

A hook 26 likewise preferably cut from the metal of the portion 17 adjacent the curved portion 19, serves to receive the end of the pin 24 whereby the device 15 may be attached or pinned to the inner fold or portion 14 of the tie 13.

The portion 17 is formed with a horizontal slit 10 26a, and the portion 27 above the slit is curved or pressed inwardly toward the wall 18 and forming a lower edge 28 acting as a stop, as will appear hereinafter.

The portion 18 of the member 16 is formed 15 with a central cut out portion 30, substantially oblong in shape, but leaving ears 31 extending from the opposite ends of the cut out, which ears are turned outwardly into perpendicular relation with respect to said portion. Said ears 20 31 are perforated, forming pivot openings 32. A clasp or friction clamp 35 provided with outwardly extending, aligned pintles 36 is mounted on and between the ears 31 by passing said pintles through the apertures 32 of the ears. The member 35 is formed with a handle portion 37 extending exteriorly of the member 16 and a portion 38 disposed at an angle to the handle 37 and projecting inwardly toward the portion 17 and below the portion 27.

The edge 11 of the shirt and the short end 13a of the tie are received between the portions 17 and 18 of the member 16. Said portions 17, 18 are sufficiently spaced to readily receive the shirt edge and the end 13a of the tie. By pressing 35 the handle downwardly, the portion 38 of the clasp 35 presses the shirt portion 11 and tie portion 13a against the portion 17, the edge 28 of the portion 27 serving as a stop to retain the portion 38 in a position disposed at right angles 40 to the plane of the portions 17 and 18, whereby the shirt edge 11 is maintained frictionally clamped.

It will now be understood that the device 15 may be removed from the tie to permit the latter 45 to be pressed, laundered or cleaned. Nevertheless, said device may be readily attached to the inner folds of the tie, being in such position completely hidden from view. By a simple manipulation of the clasp 35, to wit, by merely pressing 50 down on the handle 37, the member 15 is firmly clamped to the shirt edge 11 to prevent the member 15 from accidentally slipping off the shirt edge.

In Figs. 6 and 7 there is shown a device 15a 55

embodying the invention and illustrating a modified construction. The device 15a comprises a U-shaped member having portions 17 and 18 interconnected by a curved portion 19 for receiving the edge 11 of a shirt and the short end 13a of a tie. The portion 18 is formed with a cut-out 30. At the ends of said cut-out the metal is pressed or pouched outwardly as at 39, and said portions 39 may be formed with inwardly extending pintles 40. Mounted on said pintles 40 and extending through the cut-out 30 is a clasp 35a provided with ears 35b having openings 41 receiving said pintles 40. In other respects the clasp 35a is similar to the clasp 35 and operates in the same manner to clamp the shirt front and the tie end to the portion 17.

It will thus be seen that there is provided a device in which the several objects of this invention are achieved, and which is well adapted to meet the conditions of practical use.

As various possible embodiments might be made of the above invention, and as various changes might be made in the embodiments set forth, it is to be understood that all matter herein set forth or shown in the accompanying drawing, is to be interpreted as illustrative and not in a limiting sense.

Having thus described the invention, we claim as new and desire to secure by Letters Patent:

1. In combination with a U-shaped member adapted to receive an edge of a shirt, means for attaching said member to the inner folds of a tie worn with the shirt, said member having a cut out portion, the inner edges of said cut out portion being formed with a pair of ears, and a clasp on said member having pintles received within said ears and extending through said cut out and adapted to frictionally clamp the shirt to said member.

2. A device for attaching a tie to an edge of a

shirt, comprising a member having folded over portions interconnected at one end and adapted to receive an edge of the shirt therebetween, and a pin on the outer side of one of said portions for attachment to the inner folds of the tie, the other portion being formed with a cut out, and a friction clamp pivoted to said other portion and extending through said cut out for clamping the edge of the shirt to said first portion. 5

3. In combination, a metal member having 10 folded over portions interconnected at one end, means on one of said portions for attaching said member to a tie, said portion being slit longitudinally and the metal above said slit being pressed inwardly toward the other portion, the other portion being formed with a cut out, said member being adapted to receive the edge of a shirt between the folded over portions thereof, a clasp received within said cut out and being pivoted to said other portion, said clasp having a handle 20 portion extending exteriorly of said member, and a portion at an angle to the handle extending inwardly toward the first portion and adapted to press said edge of the shirt against said first portion, the inwardly pressed metal of the first portion serving as a stop to limit pivotal movement of said clasp. 25

4. A device for attaching a tie to an edge of a shirt, comprising a U-shaped member adapted to receive an edge of the shirt, means for attaching 30 said member to the inner folds of a tie, one arm of said U-shaped member being formed with a cut-out and the opposite edge portions of said cut-out being pressed outwardly and formed with inwardly extending pintles, and a clasp extending 35 through said cut-out and having apertured openings receiving said pintles for clamping the shirt edge to said U-shaped member.

ALBERT A. KAPLAN.

EMANUEL PORCELAIN.
